UNITED STATES PATENT OFFICE.

JAMES F. SMRZ, OF CHICAGO, ILLINOIS.

LAUNDRY-MACHINE.

1,302,868.

Specification of Letters Patent.

Patented May 6, 1919.

Application filed June 4, 1917. Serial No. 172,674.

To all whom it may concern:

Be it known that I, JAMES F. SMRZ, a citizen of the United States, residing at Chicago, in the county of Cook and State of Illinois, have invented new and useful Improvements in Laundry-Machines, of which the following is a specification.

This invention relates to laundry apparatus, and more particularly an apparatus whereby several operations are effected. It is the object of the invention to provide an apparatus or machine for washing, wringing and drying clothes, and also to associate with the machine a pair of mangle rolls for smoothing or ironing out the clothes after they are washed. The washing apparatus consists of a tank in which the clothes to be washed are placed, with means for boiling the water in the tank. In this tank or clothes boiler is mounted a container in which clothes are supported during the washing or boiling operation, and in said container operates an agitator having an alternating rotary movement. After the washing operation the container may be revolved at a high rate of speed for the purpose of wringing the water out of the clothes and drying the same. The ironing or smoothing of the washed clothes may be done at the same time the machine is washing other clothes, and by the use of the machine the usual rubber roll wringers, wash boiler, stove, flat irons, tubs, clothes lines, pins and space to dry the clothes are eliminated.

The washing operation is sanitary as the clothes are boiled continuously and dried by hot air which is generated from burners located beneath the tank, and the washing and ironing operation is easily and rapidly effected. A further advantage of the apparatus is that the person operating the same need not leave the room to hang up the clothes to dry, and the person is therefore not exposed to the danger of catching colds by passing from the hot, damp laundry room into the outside air. The apparatus is designed more particularly for domestic purposes, and as the tank containing the hot water is heated by burners connected directly to the tank, and as the water is not boiled in a separate receptacle placed on the top of a stove, there is no danger of children being scalded.

The objects and advantages of the invention pointed out hereinbefore are attained

by means of a novel combination and arrangement of parts to be hereinafter described and claimed, and, in order that the same may be better understood, reference is had to the accompanying drawings forming a part of this specification.

In the drawings,

Figure 1 is a central vertical section of the machine;

Fig. 2 is a side elevation thereof;

Fig. 3 is a front elevation;

Fig. 4 is a plan view with certain parts broken away;

Fig. 5 is a perspective view of a fragment of the clothes container showing certain structural details to be described hereinafter;

Fig. 6 is a sectional detail showing the means whereby the clothes container may be coupled up for the purpose of revolving the same;

Fig. 7 is a sectional detail showing a hood for one of the burners;

Fig. 8 is a detail in perspective showing a method of assembling the walls of the clothes container, and

Fig. 9 is a sectional detail on the line 9—9 of Fig. 4.

Referring specifically to the drawings, 10 denotes the supporting frame of the machine, the same being constructed of uprights suitably connected and braced to support two tanks or water containers 11 and 12, respectively, located one above the other, 90 and in spaced relation. The two tanks are in communication with each other through the pipe 13 leading from the bottom of the upper tank 11 and opening through the top of the bottom tank 12, said pipe being provided with a suitable valve 13^a. To the bottom of the top tank 11 is also connected an outlet pipe 14 having a suitable connection with a sewer for carrying away the dirty water after the washing operation is completed. The supporting frame of the machine also shows a pump 15 for returning the water in the bottom tank 12 to the top tank 11. As shown in Fig. 1, the pump has a valved inlet connection 15^a with the bottom 100 of the tank 12, and an outlet connection 15^b with the tank 11 near the top thereof. The pump may be an ordinary rotary pump having its drive shaft provided with a friction-wheel 16 adapted to be driven by bringing it in contact with a friction wheel 16^a to be described hereinafter.

The water in the tank 11 is adapted to be heated by means of burners 17 of any suitable type. The drawings show ordinary gas burners, but it will be understood that oil burners may be employed with equal facility. In the bottom of the tank 11 are made openings in which are mounted hoods 18 extended upward into the tank, and in which hoods the burners 17 are located, as clearly shown in Fig. 1. A leak-proof connection is provided between the hoods and the tank bottom by providing the hood with a marginal flange 18^a at its bottom, said flange being positioned to engage the under side of the tank bottom, to which it is tightly clamped by a ring 18^b secured beneath the flange by bolts 18^c passing through the ring, the flange and the tank bottom. Above the tank bottom the hood is encircled by a ring 18^d through which the bolts 18^c also pass. It will therefore be seen that upon tightening up the nuts on the bolts 18^c the hood is tightly clamped to the tank bottom and a leak-proof joint is had.

In the tank 11 is mounted a clothes container consisting of a cylinder 19 positioned vertically and composed of a side wall and top and bottom walls 20 and 21, respectively, closing the ends thereof. The top 20 of the cylinder has an opening 20^a shown in Fig. 4, said opening being for the purpose of permitting the clothes to be placed in the cylinder. As shown in Figs. 1, 4, 5, 6 and 8 of the drawings, the side wall and the bottom of the cylinder are perforated in order that the water in the tank 11 may flow into and out of the cylinder.

The side wall of the cylinder 19 is corrugated lengthwise as shown at 19^a, and the bottom of the cylinder has transverse corrugations 21^a, the aforementioned perforations being located between the corrugations. The purpose of the corrugations in the side wall and the bottom of the cylinder is to strengthen and stiffen the same.

The spaces between the corrugations 19^a at the top and bottom of the side wall of the cylinder 19 are flanged outward as shown at 19^b, leaving the corrugations projecting. The top and bottom walls 20 and 21 of the cylinder are notched at their peripheries to receive the projecting portions of the corrugations and to seat on the flanges 19^b. The projecting portions of the corrugations 19^a are split and flanged over the top and bottom walls, as shown at 19^c, thus fastening said walls to the side wall of the cylinder. This method of joining the side and the top and bottom or end walls of the cylinder makes a smooth inner surface and provides a secure fastening requiring no bolts or rivets.

In the cylinder 19 is mounted an agitator 22 carried by a shaft 23 extending into the cylinder and arranged coaxially therewith.

The agitator has an alternating rotary movement, it being given this motion by a gearing to be presently described, and when the agitator is in operation the cylinder 19 will be held stationary within the tank 11 by a latch 24 engaging a keeper-aperture in the cylinder top 20. The cylinder is so supported that it may be rotated for a purpose to be presently described. As shown in Fig. 1, the bottom of the tank carries a bearing 25 in which is stepped a spindle 25^a secured to and depending from the cylinder bottom 21 at the center thereof. To the top 20 of the cylinder is secured a plate 26 having a hub 26^a coinciding with the axis of the cylinder, through which hub the shaft 23 passes. The outer end of the hub bears against a bracket-arm 27 carried by a bracket 28, said bracket-arm being positioned inside the tank 11.

The cylinder is rotated by coupling the shaft 23 to the hub 26^a. In order that this may be done the lower end of the shaft 23 to which the agitator 22 is connected has a squared and tapered portion 23^a, and the interior of the hub 26^a is correspondingly shaped. The shaft 23 is movable in the direction of its length to wedge the part 23^a into the hub 26^a, and when this is done and the shaft 23 is rotated, the cylinder 19 is coupled to said shaft and rotates therewith. Upon sliding the shaft 23 downward and taking the part 23^a out of the hub 26^a the cylinder is disconnected from the shaft.

The lower end of the shaft 23 passes through the agitator 22 and is secured thereto by a nut 22^a, with a cover 22^b provided for said nut to prevent the same from unscrewing.

The top of the tank 11 is provided with a stationary cover 29 and a swinging cover 30, the latter being for the purpose of permitting access to the tank so that the clothes may be placed into and removed from the cylinder 19. The cover 30 is hinged to the supporting frame of the machine, one of the hinges being shown at 30^a, and when closed it rests at its free edge on the bracket member 27, the latter extending throughout the entire length of the cover 30.

The stationary cover 29 supports the bracket 28, the same being integral therewith as shown in Fig. 1. At the upper end of the bracket is a guide 31 for a slide 31^a fixed to the upper end of the shaft 23. On a bracket 32 carried by the cover 29 is fulcrumed a lever 33 having one end connected to the slide 31^a. This lever and its connection with the slide are provided for the purpose of raising and lowering the shaft 23 to couple the same to the cylinder 19 and to uncouple the same as hereinbefore described. The shaft is elevated upon swinging the handle end of the lever downward, and

upon swinging the lever in the opposite direction the shaft is lowered. A pin 33^a passing through the bracket 32 on one side of the lever 33, locks the latter. The fulcrum 5 of the lever is shown at 33^b. The connection between the lever and the slide 31^a may be made by forming the latter with a side aperture into which the end of the lever extends as shown in Fig. 1.

10 The shaft 23 is operated by the following gearing:

The supporting frame 10 carries an electric motor 34 which is the power source. It will be understood, however, that any other power source may be provided. On the shaft of the motor is a pulley 35 which is connected by a belt 35^a to a large pulley 36 positioned at the top of the frame and fast on a shaft 36^a supported in a suitable bearing bracket 37 carried by the cover 29. On the shaft 36^a are also mounted a spur-gear 38 and a pinion 39, the same being connected or formed integral so as to turn as one. This gear and pinion are slidable on the shaft 36^a and they are also connected to the shaft to turn therewith. This connection may be a spline or feather. The pinion 39 is in mesh with a spur-gear 40 on a counter-shaft 41 supported in a suitable bearing on the frame of the machine. On the gear 40 is a wrist-pin 40^a to which is attached one end of a connecting rod 42 having its other end attached to a rocker-arm 42^a loosely carried by a shaft 43. The distance of the wrist-pin 40^a from the center of the shaft 41 is less than the length of the rocker arm 42^a, and hence it will be seen that an oscillatory movement is imparted to the shaft 43 when the shaft 41 is in motion, and the rocker arm 42^a is coupled to the shaft 43. This oscillatory movement of the shaft 43 is transmitted to the shaft 23 through a bevel gearing, the shaft 43 carrying a large bevel gear 44 which is in mesh with a bevel pinion 44^a on the shaft 23. The shaft 23 extends slidably through the pinion 44^a, a driving connection being provided by a spline or feather. This sliding connection between the shaft 23 and the pinion 44^a is necessary 50 to enable the former to be slid up and down for the purpose hereinbefore described.

It will be evident that the agitator 22 receives an alternating rotary movement through the gearing hereinbefore described 55 when the motor 34 is running. In order to rotate the cylinder 19 when the shaft 23 is coupled thereto the following mechanism is provided.

On the shaft 43 is fixed a spur-gear 45 which also serves to operatively connect the rocker arm 42^a to the shaft 43 for the oscillatory movement hereinbefore described, said rocker arm having a clutch member 46 which is an integral hub exten-

sion thereof having end pins adapted to 65 enter apertures in the end of the hub of the gear 45. When the shaft 43 is to be oscillated, as hereinbefore described, by the rocker-arm 42, the clutch-member is connected to the gear 45, and upon disengaging 70 the clutch member the shaft 43 will be rotated continuously in one direction when said gear is driven. The gear 45 is driven for the purpose stated by sliding the gear 38 into mesh therewith, and when this is 75 done, the pinion 39 is disconnected from the gear 40. With the gears 38 and 45 in mesh the shaft 43 is driven from the shaft 36^a with a continuous rotary motion.

The clutch member 46 has a connection 80 with the lever 33, the connection being such that when said lever is operated to couple the shaft 23 to the cylinder 19, the clutch-member 46 is disconnected from the gear 45. This connection is made by link 47 connected to a clutch shifter lever 47^a. The lever 33 also has a connection 48 for operating the latch 24, said connection being so arranged that the latch is swung to release the cylinder 19 when the latter is coupled 90 to the shaft 23. The lever 33 also has a connection with the gears 38 and 39 for sliding the same along the shaft 36^a to engage the gear 38 with the gear 45, and to disengage said gears and bring the pinion 39 again in mesh with the gear 40. This connection is made by means of a lever 49 fulcrumed intermediate its ends to a bracket-arm 49^a extending from a frame member 50 which is an upstanding flange at 95 the edge of the cover 29. One end of this lever has a connection with the clutch member 46, and the other end of the lever is connected to the hub of the gear members 38 100 and 39.

A means is also provided for fastening the swinging cover 30 in closed position when the cylinder 19 is being rotated. This locking means is connected to the operating means of the latch 24, so that when the latch is disengaged to release the cylinder 19, the cover 30 is locked. The latch is shown provided with an extension arm 24^a 110 projecting at an angle therefrom and having connected to its outer end a latch rod 24^b extending across the top of the stationary cover 29, the outer end of said rod passing through an aperture in the bracket 28 so as to engage the inner free edge of the cover 30, it being understood that the hinge connection 30^a between said cover and the frame of the machine is at the outer edge. When the latch 24 is moved down to lock the cylinder 19, the latch rod 24^b is 115 retracted to release the cover 30, allowing the same to be swung open, but when the latch 24 is retracted to release the cylinder 120 125 19, the latch rod 24^b is advanced to lock the

cover 30. The purpose of the latch rod 24^a is to prevent access to the interior of the machine while the cylinder 19 is rotating. The cover 30 can be opened only when the cylinder 19 is not in motion.

It is thought that the operation of the machine will be understood from the foregoing detailed description but it may be summarized as follows:

- 10 The clothes being placed into the cylinder 19, and water and soap being placed in the tank 11, the burners 17 are lighted and the agitator 22 is started. After the machine has run a sufficient length of time
- 15 to wash the clothes clean, the motor 34 is stopped and the water in the tank 11 is allowed to run into the tank 12 by opening the valve 13^a. When the tank 11 is empty, the pin 33^a is withdrawn and the lever 33 is operated to slide the shaft 23 upward for the purpose of coupling the same to the cylinder 19. This movement of the lever also disconnects the mechanism whereby the shaft 23 is oscillated and
- 20 throws in gear the mechanism whereby the shaft is rotated, and after again locking the lever 33 and starting the motor 34 the cylinder 19 is rotated at a high rate of speed within the tank 11, the latter being now
- 25 empty, and the clothes, however, remaining in the cylinder. As the clothes are spun around, the centrifugal force wrings the water out of the same, it escaping through the perforations in the side and bottom of
- 30 the cylinder, the burners 17 are left lighted so that the interior of the tank is heated. The clothes are therefore spun around in the heated tank and they are rapidly wrung out in the revolving cylinder. After wringing
- 35 the clothes, clean, cold water and bluing may be run into the tank 11 and the agitating action repeated, after which the water is allowed to escape through the outlet connection 14, the clothes being now ready for
- 40 the drying operation by being again spun around as hereinbefore described. After the clothes are dried they are removed from the cylinder 19 and placed in a basket or other suitable receptacle and another batch
- 45 of clothes may be placed in the machine, the dried patch of clothes being ready for the mangling or ironing operation.

After the second batch of clothes is placed into the cylinder 19, the pump 15 will be started to pump the suds from the tank 12 back into the tank 11. The pump is operated by the following means:

The friction wheel 16^a is carried by a lever 51 fulcrumed at 51^a to the supporting frame of the machine, and said friction wheel is so positioned that when the lever is swung upward it comes in contact with the pulley 35 of the motor shaft and also with the friction wheel 16 of the pump, whereupon the pump is driven. The lever

51 also carries an idler pulley 52 which engages the belt 35^a when said lever is swung down to disengage the friction wheel 16^a from the pulley 35. After the suds has been pumped back from the tank 12 into the tank 11, the second batch of clothes is washed, and the first batch which has been removed from the machine is passed between a pair of mangle rolls 53 and 54, respectively, and ironed.

The mangle roll 54 is driven from the shaft 41, said roll being carried by a shaft 54^a having means whereby it may be coupled to the shaft 41. It will be remembered that during the washing operation the shaft 36^a 41 is receiving motion from the shaft 36^a through the gears 39 and 40, and the mangling and ironing operation may therefore be carried on while the second batch of clothes is being washed.

The mangle roll 53 is carried by a shaft 53^a, extending parallel to the shaft 54^a. These two shafts are journaled in the upturned ends 55 of a bracket member 55^a in the form of a plate positioned at one end 90 of the hinged cover 30 and hinged at 56 to one end of the supporting frame of the machine so that the mangle rolls may be dropped down to come alongside of the frame and be out of the way when the machine is not in operation, this position of the mangle rolls being shown dotted in Fig. 2.

When the mangle rolls are in operative position, the plate 55^a rests on the bracket member 27. Before the mangle rolls may be swung as stated, the shaft 54^a must be disconnected from the shaft 41. The mangle rolls are held pressed in working contact by means of a cam 57 fast on a rock-shaft 57^a having a rocker-arm 58 which is connected by a rod 58^a to a foot lever 59 fulcrumed to the supporting frame of the machine and having a ratchet or other suitable locking means 60. When this foot lever is pressed down the cam engages the shaft 53^a of the roll 53 and carries the same against the roll 54, and when the clothes are introduced between the two rollers they yield sufficiently to allow the clothes to pass therebetween.

The following means are provided for coupling the mangle roll shaft 54^a to the shaft 41: On the end of the shaft 41 is a sleeve 61 slidably mounted on said shaft and connected thereto by a feather 61^a to turn therewith. The shaft 54^a has a squared end, and the adjacent end of the sleeve is also squared on the inside so that when it is slipped over the squared end of the shaft 54^a, said shaft is coupled with the shaft 41 to turn therewith. The sleeve 61 is held in coupling position by a sliding latch 62 held advanced to engage the sleeve by a thumb screw 62^a, said latch and thumb screw being carried by the bracket 28. When the sleeve 61 is retracted and with-

drawn from the shaft 54^a, the latter is disengaged from the shaft 41 to allow the mangle rolls to be dropped down alongside the machine as hereinbefore described. The 5 sleeve 61 is journaled in an aperture in the bracket 28 and thus serves as a bearing for one end of the shaft 41. In the inner upturned end 55 of the mangle supporting frame 55^a, opposite the sleeve 61, is an aperture 63 through which said sleeve is slideable to engage the shaft 54^a. Inasmuch as the shaft 53^a is movable bodily by the cam 57 to press the mangle roll 53 against the mangle roll 54, said shaft is supported in 10 bearings which are slideable.

The bottom mangle roll 53 consists of two concentric cylinders spaced from each other. The inner cylinder 65 of this roll contains a gas or other burner 66. The inner cylinder 20 is of cast iron and the outer cylinder is of sheet iron. The inner cylinder may be heated red hot to produce a hot-air space between the two cylinders, thereby obtaining an even temperature over the whole 25 surface of the outer cylinder.

I claim:

1. In a laundry machine, a receptacle for a washing fluid, a clothes container in the receptacle mounted for rotary movement therein, the walls of said container being perforated, a rotary agitator in the container, a shaft carrying the agitator, driving means for the shaft, cooperating clutch members on the shaft and the container for coupling 35 the container to the shaft to rotate therewith, and means for holding the container stationary in the receptacle when uncoupled from the agitator.

2. In a laundry machine, a receptacle for a washing fluid, a clothes container in the receptacle mounted for rotary movement therein, the walls of said container being perforated, a rotary agitator in the container, a shaft carrying the agitator, driving means 40 for the shaft, cooperating clutch members on the shaft and the container for coupling the container to the shaft to rotate therewith, the agitator shaft being movable in the direction of its length to couple to and uncouple from the container, and means for holding the container stationary in the receptacle when uncoupled from the agitator.

3. In a laundry machine, a receptacle for

a washing fluid, a clothes container in the receptacle mounted for rotary movement therein, the walls of said container being perforated, an agitator in the container, means for imparting either an alternating rotary movement or a continuous rotary movement to the agitator, means for coupling the container to the agitator to rotate therewith when it is given the continuous rotary movement, and means for holding the container stationary in the receptacle when it is uncoupled from the agitator.

4. In a laundry machine, a receptacle for a washing fluid, a clothes container in the receptacle mounted for rotary movement therein, the walls of said container being perforated, an agitator in the container, a shaft 70 carrying the agitator, means for imparting either an alternating rotary movement or a continuous rotary movement to the shaft, means for holding the container stationary with respect to the receptacle when the shaft 75 is given an alternating rotary movement, means for coupling the container to the shaft when the latter is given the continuous rotary movement, the shaft and the container having coacting clutch members and 80 the shaft being movable in the direction of its length to engage and disengage said clutch members.

5. In a laundry machine, a receptacle for a washing fluid, a clothes container in the receptacle mounted for rotary movement therein, the walls of said container being perforated, an agitator in the container, a shaft carrying the agitator, means for imparting either an alternating rotary movement or a 90 continuous rotary movement to the shaft, means for holding the container stationary with respect to the receptacle when the shaft is given an alternating rotary movement, means for coupling the container to the shaft 95 when the latter is given the continuous rotary movement, the shaft and the container having coacting clutch members and the shaft being movable in the direction of its length to engage and disengage said clutch 100 members, means for effecting said longitudinal movement of the shaft, and a connection between said means and the aforesaid holding means of the container.

In testimony whereof I affix my signature. 105
JAMES F. SMRZ.
